No. 36,344.

Patented June 2, 1903.

UNITED STATES PATENT OFFICE.

THEODORE F. FURNESS, OF PHILADELPHIA, PENNSYLVANIA.

DESIGN FOR TILING.

SPECIFICATION forming part of Design No. 36,344, dated June 2, 1903.

Application filed April 27, 1903. Serial No. 154,603. Term of patent 14 years.

To all whom it may concern:

Be it known that I, THEODORE F. FURNESS, a citizen of the United States, residing at Philadelphia, Pennsylvania, have invented a new, original, and ornamental Design for Tiling, which is fully shown in the accompanying drawing, to which reference is made.

I claim as my invention—

The ornamental design for tiling, substantially as shown in the accompanying drawing.

In testimony whereof I have signed my name to this specification in the presence of two subscribing witnesses.

THEODORE F. FURNESS.

Witnesses:

MURRAY C. BOYER,
JOS. H. KLEIN.
